UNITED STATES PATENT OFFICE.

ALPHEUS W. MONTGOMERY, OF NEW YORK, N. Y.

MACHINE FOR CLEANING FIBERS.

No. 910,406.

Specification of Letters Patent.

Patented Jan. 19, 1909.

Application filed November 24, 1905. Serial No. 288,842.

To all whom it may concern:

Be it known that I, ALPHEUS WOODS MONTGOMERY, a citizen of the United States, residing in the borough of Queens, county of 5 Queens, city and State of New York, have invented certain new and useful Improvements in Machines for Cleaning Fibers, of which the following is a specification.

This invention relates to machinery for 10 cleaning or decorticating fibers, more especially such as banana fibers, or others of that character.

The object of the invention is to provide 15 improved mechanism whereby the stalks or stems will be subjected, first to a crushing action by suitable means, such as rolls preferably fluted and oppositely driven, and which will act also as feeding rolls and advance the article to the subsequent scraping 20 mechanism of the machine. The stalk will be further treated by a scraping process by suitable coöperating mechanism located beyond the crushing mechanism; this scraping mechanism being driven at a surface 25 speed greater than that of the crushing rolls, and may consist, as herein shown of suitably arranged coöperating blades or scraping knives, whereby the soft and pulpy portions 30 of the stems or stalks, that have been somewhat disintegrated by the crushing mechanism, will be worked off and separated from the fibrous portion of the stalk.

A further feature of the present invention 35 relates to the organization, with the mechanism for preliminary treatment of the stalks, such as crushing mechanism, and mechanism for subsequently scraping and cleaning the pulpy material from the fibrous portion, of supplemental cleaning mechanism located 40 between the crushing mechanism or rolls, and the main scraping mechanism already mentioned. And in combination with such supplemental scraping mechanism, is provided connecting means for so controlling 45 the supplemental mechanism as to render the same inoperative at one stage of the process, and also to automatically bring the supplemental scraping mechanism into operative position at another stage in the operation 50 upon the same stalk or stem, whereby to clean or scrape the rearward end of the stalk that is being fed through the machine; the remaining or forward portion of the stalk having been cleaned by the previously mentioned advance scraping mechanism operat- 55

ing in conjunction with the crushing mechanism, as has been set forth.

A further feature of the present invention relates to mechanism for operating upon the stalk after its entire length has been subjected to the crushing and treating mechanisms, as hereinbefore set forth and removing therefrom the pulpy or cellulose portion, which may be accomplished by directing one or more streams of water onto the stalks 60 while being conveyed along upon a conveyer provided with suitable openings through which the particles of pulp will be forced, permitting the fibrous portion of the stalk to continue along the conveyer. Thereupon, 65 the fibrous portions are somewhat condensed by being caused to pass through a conductor somewhat hopper-shaped and thence through or between a suitable pair of rollers. The condensing action in the hopper may be assisted by directing jets of air from each side 70 whereby the fibers are moved toward the middle portion. The latter portion may also include means for removing the moisture from fibers, and the air blasts directed into 75 the hopper may furnish air suitably heated which will both condense the fiber and remove moisture therefrom.

In the accompanying drawings, illustrating an embodiment of the present invention, 80 Figure 1 shows part of the machine in side elevation. Fig. 2 is a vertical section through the crushing and supplemental cleaning mechanisms, showing the operation upon a stalk at an intermediate stage. Fig. 90 3 is a similar view showing the treatment of a stalk at a later stage. Fig. 4 is a front elevation of the machine. Fig. 5 is a vertical section on the line 5—5 indicated in Fig. 1. Fig. 6 is an elevational view showing the forward 95 end of the machine. Fig. 7 is a plan view of the forward portion of the machine; and Fig. 8 is a detail of the forward scraper.

The main frame A of the machine is provided with sets of standards arranged in 100 pairs on opposite sides of the machine for supporting and guiding for vertical movement, the bearings of the shafts for the several rotary members. At the front of the machine, adjacent a suitable feeding table B, 105 are arranged the pair of initial crushing rolls 7 and 8, that are preferably fluted as shown in Fig. 2. Beyond these rolls, may be provided additional fluted crushing rolls if desired, one pair of rolls 9 and 10, and another 110

pair of rolls 11 and 12 being shown, with their engaging portions in substantially the same horizontal plane as that of the crushing rolls 7 and 8. These supplemental crushing rolls may be arranged with the lower roll having its shaft bearing stationary, while the bearing blocks of the upper roll of each of these pairs may be movable vertically in the uprights and normally pressed against the lower rolls by suitable springs 14.

Beyond the sets of crushing rolls is arranged a scraping or cleaning mechanism, denoted generally by C, and which is shown to comprise two endless belt members arranged to travel in substantially parallel planes for a portion of their movement.

The lower member of the cleaning means comprises an endless chain member 15, passing around oppositely disposed spur wheels 16 and 17, which latter may be positively driven to actuate the chain. The chain may also pass over a suitable guide wheel 18 if desired. The wheels are arranged in pairs on suitable shafts 19 and 20, and carry two such chains 15; and across between the parallel chains extend bars 21. These bars are free to rotate and each carries a pair of scraping plates 22. The chain member is guided between the spur wheels 16 and 17 adjacent the upper chain by means of suitable dogs 23 on the end of each of the bars 21 that engage and slide along suitable guide strips 24 as shown in Fig. 5. By this means, the scraping plates 22 are caused to travel at a fixed angle during operation as indicated in Fig. 1, wherein it will be seen that the ends of alternate plates travel in the same plane, giving a wavy effect to the stalk pressed thereon by the upper chain member.

The member coöperating with this lower belt member, comprises a pair of chain members 25 passing around spur wheels 26 and 27, a pair of each being mounted on shafts 28 and 29 respectively. These chains are connected by suitable cross bars 30, each of which carries a blade 31 and also carries dogs 32 engaging a suitable guide plate 33, whereby the chain member will operate to cause the blades 31 to travel adjacent to the blades 22 of the lower chain, and preferably alternate therewith for giving a wavy effect to the stalk. The shaft 20 may be positively driven by a chain 34 from a gear 35 on the shaft 36. And the shaft 29 of the upper chain member may be driven by a gear 37 thereon, meshing with a similar gear 38 fast on the shaft 20; the chain members being thereby driven at an equal surface speed. The crushing rolls are driven from the shaft 36 by suitable gear connections so that their surface speed relative to that of the scraping mechanism C, just described, will be much slower, it being found practicable to have the surface speed of the endless chain members 65 of the scraping mechanism about ten times

more or less that of the surface speed of the crushing rolls, or at least that of the initial crushing rolls 7 and 8.

In the machine set forth, a pulley 40 is driven from any suitable source of power. The pulley 40 as shown in Fig. 3 drives a pinion 42 fast on shaft 36, meshing with a gear 43; and the gear 43 engages with a gear 44, fast on the shaft of the lower crushing roll 11, and also meshes with a gear 45 fast on the shaft of the crushing roll 9. A gear 46 meshes with the gear 45, and also with a gear 47 fast on the shaft of the initial crushing roll 7, whereby the latter is driven. As set forth in Fig. 1, the lower crushing roll 7 drives its companion roll 8 by means of gears 48 and 49; the lower crushing roll 9 drives the roll 10 by means of gears 50 and 51; and the lower crushing roll 11 drives its companion roll 12 by means of gears 52 and 53, all of which gears are fast on the shafts of the respective rolls, and are provided with elongated teeth whereby a slight separation will not disengage them.

With the mechanism already set forth, a stalk being fed into the crushing rolls and thereby passed along into engagement with the scraping mechanism C, will be scraped by the latter as long as it is in engagement with the crushing rolls, because of the greater surface speed of the scraping means. But after the stalk leaves the final crushing roll or rolls, it will be merely advanced, and to a certain extent perhaps compressed, by the scraping means for the remainder of its length, because it has now no retarding means necessary to cause the scraping action. That is, the length of the stalk equal to the distance from the last crushing roll to the scraping device C, will not receive the scraping operation in the device C, to which the other portion of the stalk has been subjected. To obviate this deficiency, supplemental scraping means or members are located between the scraping mechanism C, and the crushing rolls or sets of rolls. In the present instance, a pair of rotary scraping members 60 and 61 are mounted between the frame sides and comprise essentially radially arranged scraping blades 62 mounted on suitable shafts 63 and 64. The shaft 63 has a gear 65 fast thereon, meshing with a larger gear 66, fast on the shaft of the lower crushing roll 11. And the lower rotary scraping member 60 is driven from the upper scraping member by means of engaging gears 67 and 68 fast on the shafts 63 and 64 respectively of these members. The driving gear 66 for the rotary scrapers being larger than gear 65, causes these members to have a surface speed slightly greater than that of the initial crushing rolls 7 and 8.

Suitable connecting mechanism is provided whereby the rotary scrapers are retained out of operative position while the

initial crushing rolls 7 and 8 are in engagement with a stalk, and which mechanism, when the stalk has been advanced beyond the initial crushing rolls will be brought into 5 operative position to treat a stalk passing therebetween.

In Figs. 1 to 3 is shown a connecting mechanism whereby the relative separation of the rolls 7 and 8 causes a separation of the rotary scrapers 60 and 61, and the relative approach of the crushing rolls 7 and 8 brings the rotary scrapers into operative position to treat a stalk. One of the initial crushing rolls is reciprocated by connecting rods pivoted to levers or beams 70, suitably pivoted on arms 71, which levers, through suitable connecting rods, move one of the rotary scraping members in an opposite direction to that of the crushing rolls. The lower crushing roll 7 may have its shaft mounted in fixed bearings, while the bearings for the shaft of the upper crushing roll 8 may be attached to the connecting rods 72 pivoted to the levers 70. Each connecting rod 72 is normally 25 forced downward by a spring 73 tending to retain these crushing rolls in engagement. The upper rotary scraper 61 has the bearings of its shaft fixed in frame A, while the bearings for the shaft 64 of the lower rotary 30 scraper are vertically movable and attached to connecting rods 74, whose upper ends are pivoted to the levers 70. By this connecting mechanism, it will be seen that the springs 73 normally retain the rolls 7 and 8 and also 35 the rotary scrapers 60 and 61, in engaging positions.

Upon a stalk being fed in between the crushing rolls 7 and 8, they will be separated, as shown in Fig. 2, and serve to advance the 40 stalk and at the same time crush it. This separation of these crushing rolls by the movement upward of the roll 8, will, through the connecting mechanism, cause a downward movement of the lower scraping member 60, which will bring it out of operative 45 position, as shown in Fig. 2; and the stalk will pass freely between the scrapers into engagement with the advance scraping mechanism C. But when the stalk shall 50 have advanced beyond the initial crushing rolls 7 and 8 as shown in Fig. 3, the spring 73 will at once bring these rolls together by lowering the upper roll 8, which operation, through the connecting mechanism, will 55 return the lower scraper to operative position as shown in this figure. When the advance of the stalk by the movement of the advance scraping mechanism C, is no longer retarded by the slower movement of the 60 crushing rolls, this mechanism C, will act practically as a conveyer to advance the stalk at its surface speed, and since such surface speed is much greater than that of the 65 rotary scraping members 60 and 61, these latter members now being in operative posi-

tion, will serve to scrape the rear end portion of the stalk, that otherwise would have been advanced through the final scraping means C, without the desired scraping treatment.

Just beyond the delivery portion of the 70 scraping member C, on a suitable portion of the frame A, is arranged a horizontal perforated carrier member that may comprise a chain belt D. The links of this belt are separated to form a number of open spaces 75 through which the pulpy portion of the stalk may be driven by streams of water directed upon the stalk while passing along this chain member. The chain belt D is supported on rollers 75 and 76, the latter serving to drive 80 the belt, and being driven by a chain 77 from the shaft 20. A series of pipes 78, extend transversely across the belt member D from a pipe 79 and each of the pipes 78 are provided with nozzles 80 directed toward the 85 member D. As the stalk passes along over this moving belt member, streams of water from the nozzles 80 impinge on the stalk and cause the pulpy portion to pass downward through the openings d in the belt member. 90

Upon the stalk leaving the belt member D, it is passed into a somewhat hopper-shaped member E that serves to condense the fibrous stalk, and leads it between a pair of rollers 81 and 82. These rollers are driven from the 95 shaft 75 by means of a chain 90. In this member E, the stalk is made more narrow before passing between the rolls and such action is assisted by means of a blast of air being directed on each side through suitable 100 pipes 83 and 84 that lead inward at each side of the member E. The pipes 83 and 84 connect with a feed pipe 85 through suitable pipes 86 and 87.

If desired, heated air from any suitable 105 source, may be furnished to the pipes 83 and 84, by which means the fiber is dried at the same time that it is condensed into a more compact form.

While the stalk is passing between the two 110 chains of the scraping member C, the pulp and fiber will have a certain tendency to adhere to the blades of the chain members especially to the blades of the lower member. To loosen the pulp and fiber from such blades, 115 blasts may be directed upon the blades, and means are shown for directing air upon the blades of the lower chain from below as they pass over the sprocket wheel 17. A pipe 88 extends across the machine adjacent the 120 sprocket 19, and has a series of nozzles 89 directed toward the shaft 20, slightly before it whereby the air emerging from these nozzles, will strike the blades of the lower chain.

If desired, the pipe 88 may be connected 125 with the feed pipe 85 that furnishes a supply of air for the nozzles 83 and 84 of the member E.

Having thus described my invention, I claim:

1. In a fiber treating machine, the combination of crushing means, scraping means arranged beyond the crushing means, supplemental scraping means arranged between the crushing means and the said scraping means, mechanism connecting the crushing means with the supplemental scraping means arranged to retain the supplemental scraping means out of operative position while the stalk is engaged by the crushing means, and to hold the supplemental scraping means in operative position when the stalk is not engaged by the crushing means, and actuating mechanism arranged to operate the second scraping means at a surface speed greater than that of the supplemental scraping means.
2. In a fiber treating machine, the combination of crushing means, scraping means arranged beyond the crushing means, supplemental scraping means arranged between the crushing means and the said scraping means, mechanism connecting the crushing means with the supplemental scraping means arranged to retain the supplemental scraping means out of operative position while the stalk is engaged by the crushing means, and to hold the supplemental scraping means in operative position when the stalk is not engaged by the crushing means, and actuating mechanism arranged to operate the supplemental scraping means at a surface speed greater than that of the crushing means and to operate the other scraping means at a surface speed greater than that of the supplemental scraping means.
3. In a fiber treating machine, the combination of crushing means, scraping means arranged beyond the crushing means, supplemental scraping means arranged between the crushing means and the scraping means, mechanism connecting the crushing means with the supplemental scraping means arranged to retain the supplemental scraping means out of operative position while the stalk is engaged by the crushing means, and to hold the supplemental scraping means in operative position when the stalk is not engaged by the crushing means, actuating mechanism arranged to operate the second scraping means at a surface speed greater than that of the supplemental scraping means, and one or more sets of crushing means arranged between the said crushing means and the supplemental scraping means.
4. In a fiber treating machine, the combination of a pair of crushing rolls, one of the rolls being movable to and from the other roll, stalk scraping means, a pair of rotary scraping members arranged between the said crushing rolls and said scraping means, one of the rotary scraping members being movable to and from the other member, mechanism connecting the movable crushing roll with the movable rotary scraping member whereby the recession and approach of the crushing roll will cause the approach and recession respectively of the rotary scraping member, means for retaining the rotary crushing and scraping members normally together, and actuating means arranged to operate the said scraping means at a surface speed greater than that of the rotary scraping members.
5. In a fiber treating machine, the combination of a pair of crushing rolls, one of the rolls being movable to and from the other roll, scraping mechanism arranged beyond the crushing rolls and comprising endless chain members carrying blades arranged to scrape and also advance an article passed therebetween, a pair of rotary scraping members arranged between the said crushing rolls and said scraping mechanism, one of the rotary scraping members being movable to and from the other member, mechanism connecting the movable crushing roll with the movable rotary scraping member whereby the recession and approach of the crushing roll will cause the approach and recession respectively of the rotary scraping member, means for retaining the rotary crushing and scraping members normally together, and actuating means arranged to operate the said scraping mechanism at a surface speed greater than that of the rotary scraping members.
6. In a fiber treating machine, the combination of crushing means, scraping means beyond the crushing means, supplemental scraping means arranged intermediate of said crushing and scraping means, and connections between the crushing means and the supplemental scraping means arranged to retain the supplemental scraping means out of operative position while the fiber is engaged by the crushing means.
7. In a fiber treating machine, the combination of a pair of crushing rolls relatively movable to cause their approach and recession, means for rotating said rolls, a pair of rotary scraping members beyond the crushing rolls and relatively movable to cause their approach and recession, scraping means arranged beyond the rotary scraping members, means for causing the approach and recession of the crushing rolls to effect a recession and approach respectively of the rotary scraping members, actuating mechanism arranged to operate the rotary scraping members at a surface speed greater than that of the crushing rolls, and also arranged to operate the scraping means at a surface speed greater than that of the rotary scraping members.
8. In a fiber treating machine, the combination of a pair of crushing rolls, a pair of rotary scraping members beyond the crushing rolls, scraping mechanism arranged beyond the scraping rolls, one of the crushing

rolls being movable to and from the other roll, one of the rotary scraping members being movable to and from the other member, pivoted levers carried by the frame of the 5 machine, connecting rods between the movable crushing roll and the ends of said levers, connecting rods between the other ends of said levers and the movable scraping member, and a spring arranged to normally retain the crushing rolls together and scraping 10 members out of operative position.

9. In a fiber treating machine, the combination of a pair of crushing rolls, a pair of rotary scraping members arranged beyond the 15 crushing rolls, scraping mechanism arranged beyond the rotary scraping members and comprising endless belt members carrying blades arranged to scrape and also to advance an article passed therebetween, one of 20 the crushing rolls being movable to and from the other roll, one of the rotary scraping members being movable to and from the other member, pivoted levers carried by the frame of the machine, connecting rods between 25 the movable crushing roll and the ends of said levers, connecting rods between the other ends of said levers and the movable scraping member, a spring arranged to normally retain the crushing rolls together and 30 rotary scraping members out of operative position, supplemental crushing rolls located between said crushing rolls and said rotary scraping members, and actuating mechanism arranged to operate the rotary scraping 35 members at a surface speed greater than that of the crushing rolls, and arranged to operate the said scraping mechanism at a surface speed greater than that of the rotary scraping members.

40 10. In a fiber treating machine, the combination of a pair of crushing rolls, a pair of scraping rolls beyond the crushing rolls, scraping mechanism arranged beyond the scraping rolls and comprising endless chain 45 members carrying blades arranged to scrape and also to advance an article passed therebetween, one of the crushing rolls being movable to and from the other roll, one of the scraping rolls being movable to and from the 50 other scraping roll, a pivoted lever carried by

the frame of the machine, a connecting rod between the movable crushing roll and one end of said lever, a connecting rod between the other end of said lever and the movable scraping roll, a spring arranged to normally retain the feed rolls together and scraping rolls out of co-operative position, and supplemental feeding and crushing rolls located between said feeding rolls and said scraping rolls.

11. In a fiber treating machine, the combination with means for crushing and scraping a stalk, of conveying means having openings therethrough, means for directing streams of water upon a stalk on said conveyer, a pair of rollers arranged beyond said conveyer, a hopper-shaped conductor arranged to receive the fiber from the conveyer and direct it between said rollers, and means for directing a stream of air at each side of the hopper to condense the fiber into a more compact form.

12. In a fiber treating machine, the combination with crushing mechanism, of scraping mechanism comprising endless chain 75 members carrying blades and means for directing one or more streams of air through the lower of said endless members.

13. In a fiber treating machine, the combination with crushing mechanism, of scraping mechanism comprising endless chain 80 members carrying blades, means for directing one or more streams of air through one of said endless members, a conveyer arranged to receive the stalk from said scraping mechanism and provided with openings therethrough, means for removing the non-fibrous particles through the openings in said conveyer, and means for receiving the fiber from said latter conveyer and condensing it into a 85 more compact form, said latter means including conduits for directing air streams upon opposite sides of the fiber.

Signed at Nos. 9 to 15 Murray street, New York, N. Y., this 21st day of November, 1905. 95

ALPHEUS W. MONTGOMERY.
